US00D611919S

(12) **United States Design Patent**
Kucera

(10) **Patent No.:** **US D611,919 S**
(45) **Date of Patent:** **** Mar. 16, 2010**

(54) **CEILING-MOUNTED MONITOR SYSTEM**

7,604,274 B2 * 10/2009 Vitito 296/37.8

(75) Inventor: **Curtis C. Kucera**, Temecula, CA (US)

* cited by examiner

(73) Assignee: **Rosen Entertainment Systems, L.P.**,
Corona, CA (US)

Primary Examiner—Antoine D Davis

(74) *Attorney, Agent, or Firm*—Kolisch Hartwell, P.C.

(**) Term: **14 Years**

(57) **CLAIM**

(21) Appl. No.: **29/336,871**

The ornamental design for a ceiling-mounted monitor system, as shown and described.

(22) Filed: **May 11, 2009**

DESCRIPTION

(63) Continuation of application No. 29/297,024, filed on Nov. 1, 2007, now abandoned.

FIG. 1 is an inverted, front perspective view of the design of the invention, with the panel-component in the deployed position (“the Deployed Position”).

(51) **LOC (9) Cl.** 14-03

FIG. 2 is an inverted, back perspective view of the design of the invention, with the panel-component in the Deployed Position.

(52) **U.S. Cl.** **D14/132**

FIG. 3 is an inverted, front perspective view of the design of the invention, with the panel-component in the stowed position (“the Stowed Position”); and,

The stippling and shading lines shown in the drawings represent the approximate three-dimensional contour of the design, and are not intended to indicate surface decoration. Environment is shown by evenly spaced dash-double-dot-broken lines.

Portions of the ceiling-mounted monitor system that are not shown in the drawing(s) form no part of the claimed design.
